(57) **CLAIM**

The ornamental design for a protective cover for display, as shown and described.

DESCRIPTION

FIG. 1 is a perspective view of a protective cover for display showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, showing the protective cover for display in a open position;

FIG. 9 is a perspective view showing the practical usage thereof;

FIG. 10 is the other perspective view showing the practical usage thereof; and,

FIG. 11 is another perspective view showing the practical usage thereof.

The broken lines showing are for illustrative purpose only and form no part of the claimed design.

1 Claim, 9 Drawing Sheets
